UNITED STATES PATENT OFFICE.

HENRY JACOBSON, OF MILWAUKEE, WISCONSIN.

HYDRAULIC BALING PRESS.

Application filed August 17, 1925. Serial No. 50,742.

The invention relates to baling presses, and more particularly to baling presses of the hydraulic type.

In hydraulic baling presses it is necessary to limit the extent of movement of the ram or pressing head, but in presses used for baling scrap metal and other hard substances the usual forms of stop mechanism for the ram have not been suitable, and it is one of the objects of this invention to provide stop mechanism for the ram which will prevent the lodgment of scrap, from the press, upon parts of said mechanism and thus provide for efficient operation of the press.

In hydraulic presses it is common to use studs, secured to the flange on the cylinder, for holding or connecting the stuffing-box glands thereto. The boring of holes in the cylinder flange weakens the flange and thus makes it liable to rupture or cracking. To obviate this difficulty I have provided a novel cylinder construction in which the hydraulic cylinder is provided with a double flange, the upper flange only carrying the bolts to connect the stuffing box gland to the cylinder, and said bolts having a detachable connection with the upper flange on the cylinder. By this construction strains ordinarily produced on the main cylinder flange, by the stuffing-box bolts, are eliminated, and such strains are taken by a separate flange.

The invention further consists in the several features hereinafter set forth and more particularly defined by claims at the conclusion hereof.

In the drawings: Fig. 1 is a view of a press provided with the features embodying the invention, parts being broken away and parts being shown in section, the view being taken looking at one side of the ram;

Fig. 2 is a view similar to Fig. 1, being taken looking at another side of the ram, and parts being broken away;

Fig. 3 is a detail sectional view taken on the line 3—3 of Fig. 1.

In the drawings the numeral 4 designates a press box, which may be of any suitable construction, and 5 a ram adapted to work in said box to compress material therein. The ram 5 is secured to its piston 6 by bolts 7 passing through cooperative flange portions 8 and 9 on the ram and piston, respectively, said piston working in an hydraulic cylinder 10 into which the high

pressure fluid is introduced through a pipe 11 connected to a conduit 12 integral with the cylinder 10 and depending from the lower end thereof so that the pipe connection does not weaken the side walls or bottom of the hydraulic cylinder.

The hydraulic cylinder 10 is shown mounted in a frame or support 13 which, in the present case, is shown as associated with tension rods 14 which connect with other parts of the press, not shown.

The piston 6 of the ram works in the cylinder 10 and through a stuffing-box including packing 15, a follower ring 16 and a gland ring 17. The gland ring 17 is usually connected by bolts anchored in a single flange of the cylinder but in the present invention the cylinder is provided with spaced flanges 18 and 19, the upper flange 19 being designed to take the bolts and thus relieve the lower flange 18 of any strain occasioned by the bolts that connect the gland 17 to the cylinder.

As shown, the gland 17 is provided with a series of holes through which bolts 20 pass, and these bolts are connected to the flange 19 by providing radial slots 21 alined with said holes in the ring 17 so that the shanks of the bolts may pass through said slots, and the heads of the bolts are seated against the lower face of the flange 19 and within an annular recess 23 formed between the flanges 18 and 19. The bolts 20 are tightened against the ring 17 by nuts 24 engaging the outer side of said ring.

The use of slots in the flange 19, instead of tapped openings, eliminates the possibility of cracks and strains that may develop during the tapping process that is usually employed. Thus, it will be noted, that the packing ring gland is secured to the cylinder without imposing a strain on the main flange of the cylinder and in a manner to prevent possible rupturing of the flange to which the bolts are attached.

As is well understood, the passage of pressure fluid through the pipe 11, projection 12 and into the cylinder 10 puts pressure on the piston 6 and lifts the ram which then is raised until it comes against a fixed stop.

In order to eliminate the difficulties that have been experienced with the usual types of stops, particularly in connection with baling presses for scrap metal, I have provided cooperative stops on the relatively fixed parts of the press and the ram, consisting of

hardened steel stop bars 25 secured by bolts 25' to the fixed framework of the press, and similar bars 26 secured by bolts 27 to the ram, and each of these bars has an angular 5 contacting face 28 which slopes downwardly so that with a vertical press if any scrap metal works out between the ram 5 and the press box it will not lodge between the stops but will fall or slide down the inclined surface of the stops and hence prevent any interference with the proper action 10 of the stop mechanism.

I desire it to be understood that this invention is not to be limited to any particular 15 form or arrangement of parts except in so far as such limitations are specified in the claims.

What I claim as my invention is:

1. In an hydraulic press, the combination 20 with a press box, a vertically disposed, hy-

draulically operated ram working in said box, of a fixed stop, and a stop on the ram engageable with said fixed stop for limiting the upward movement of the ram, each of said stops having inclined surfaces to prevent the lodgment between them of any material escaping from the press box. 25

2. In an hydraulic press, the combination with a press box, a vertically disposed ram working therein, of removable and renewable stops for limiting the upward movement of the ram, one of said stops being secured to the relatively fixed parts of the press and the other to the ram, said stops having inclined contacting surfaces to prevent lodgment between them of any material escaping from the press box. 30 35

In testimony whereof, I affix my signature.

HENRY JACOBSON.
